FIG. 6 is a partial side view of another applicator strip embodiment of the invention;

FIG. 7 is a cross-sectional view of the applicator strip shown in FIG. 6 taken along lines 7—7;

FIG. 8 is a schematic view of processing apparatus suitable for use with the applicator strip shown in FIGS. 6 and 7; and

FIG. 9 is a schematic view of processing apparatus suitable for practicing another processing method of the invention.

Referring now to FIGS. 1 and 2, there is shown a portion of the matrix 15 formed by an elongated strip of sorbent, compressible material. The open pored matrix strip 15 includes the rear surface 16 and the front or applicator surface 17. Impregnated in the central portion of the matrix 15 is a quantity of fluid processing reagent 18. Straddling the reagent filled central region of the matrix 15 and directly adjacent the front 17 and rear 16 surfaces thereof are the matrix boundary layers 19 and 21 which are substantially free of fluid reagent.

In a typical example, the matrix 15 is formed of open pored, reticulated polyurethane foam having a thickness of about $\frac{1}{8}$ inch, a width w corresponding to the width of the film strip being processed and approximately 110 pores per square inch. It is desirable that the processing reagent 18 have a viscosity of at least 1,000 centipoises (cps.) and preferably of about 10,000 cps. The relatively high viscosity enhances the locational stability of the reagent within the matrix 15. The reagent can comprise a conventional liquid processing reagent to which a suitable thickener has been added to establish the proper viscosity. Examples of suitable thickeners include, for example, natural and synthetic polysaccharides, enzymes, starches, thermoplastic and thermosetting acrylic resins, etc.

According to one method, the matrix 15 is prepared by passing the surface 17 by a reagent supply nozzle (not shown) that forces the reagent 18 into the matrix to a depth determined by the desired thickness of the lower boundary level 21. This depth is established by controlling the discharge pressure of the fluid reagent and/or the contact pressure between the nozzle and the surface 17. The impregnated matrix 15 then is passed into contact with a doctor blade (not shown) that penetrates the surface 17 to a depth desired for the upper boundary layer 19. In this way reagent is removed from the upper boundary layer 19 leaving both upper 19 and lower 21 boundary layers substantially free of reagent 18.

FIG. 3 schematically illustrates process apparatus utilizing the applicator strip shown in FIGS. 1 and 2. The matrix strip 15 is wound in the roll 22 which is mounted for rotation in enclosure 20. Because of the reagent free boundary layers 19 and 21, the individual layers of reagent 18 within the roll 22 are isolated from each other. Thus, undesirable sticking of the contacting front and rear surfaces 16 and 17 is prevented. Prior to use, the roll 22 is preferably retained in a suitable hermetically sealed container to prevent oxidation of the impregnated reagent 18. Also rotatably mounted within the enclosure 20 is the roll of film 23 to be processed. Both the matrix strip 15 and the film 24 are passed between the adjacent roller members 25 and 26 and onto, respectively, the matrix strip takeup reel 27 and the film strip takeup reel 28.

The spacing between the roller members 25 and 26 is such as to produce pressurecontact between the applicator surface 17 and the film strip 24. The resultant compression of the matrix strip 15 forces the fluid reagent 18 out of the open pores in the applicator surface 17 and onto the surface of the film strip 24. The roller members 25 and 26 also exert a tangential force which tends to deform the compressible matrix strip 15 slightly in a direction parallel to the surface of the film strip 24. This slight movement of the applicator surface 17 with respect to the adjacent film strip 24 spreads the discharged reagent

18 evenly over the surface of the film strip 24 thereby insuring uniform processing.

Thus, the present invention provides a reagent applicator and processing method that permit, without expensive equipment, the controlled application of film processing reagent. It will be appreciated that the applicator and method are uniquely suited for viscous processing of continuous film strips. In addition, the reagent impregnated matrix strip 15 alleviates problems related to storage of the processing reagent prior to its use.

FIGS. 4 and 5 show another embodiment of the invention comprising the elongated matrix strip 31 impregnated with a fluid processing reagent 32. The strip 31 is similar to that shown in FIGS. 1 and 2 except that the reagent free boundary layers 19 and 21 are eliminated. In this embodiment, the matrix strip 31 is retained by the elongated support band 33 having the bottom wall 34 that supports the rear surface 35 of the strip 31. The support band 34 also possesses side walls 36 which cover the edges 37 of the matrix strip 31. Thus, all surfaces of the strip 31 with the exception of the open pored applicator surface 38 are covered by the support band 33 which is formed of a suitable flexible, non-compressible substance such as Mylar or similar polyester material.

FIG. 4 and 5 show another embodiment of the invention comprising the elongated matrix strip 31 impregnated with a fluid processing reagent 32. The strip 31 is similar to that shown in FIGS. 1 and 2 except that the reagent free boundary layers 19 and 21 are eliminated. In this embodiment, the matrix strip 31 is retained by the elongated support band 33 having the bottom wall 34 that supports the rear surface 35 of the strip 31. The support band 34 also possesses side walls 36 which cover the edges 37 of the matrix strip 31. Thus, all surfaces of the strip 31 with the exception of the open pored applicator surface 38 are covered by the support band 33 which is formed of a suitable flexible, non-compressible substance such as Mylar or similar polyester material.

The applicator strip 31 is preferably used with processing equipment of the type shown in FIG. 3 and in the manner described above. However, the spacing d between the band's side walls 36 must be greater than the widths of both the film strip being processed and the upper roller member 25 allowing them to project into the cavity formed by the support band 33 and compress the matrix 31. An advantage of this embodiment is that when wound into a cylindrical roll for storage the upper edges of the side walls 36 seat against the adjacent bottom wall 34 thereby preventing inadvertent compression of the retained matrix 31.

The embodiment shown in FIGS. 6 and 7 is similar to that shown in FIGS. 1 and 2 except that the matrix strip 41 possesses only one boundary layer 43 free of fluid processing reagent 42. Covering the applicator surface 45 is the spacer sheet 46 which serves the same function as the additional boundary layer shown in the embodiments of FIGS. 1 and 2, i.e. to isolate separate layers of the reagent 42 when the matrix strip 41 is wound into a cylindrical roll for storage.

FIG. 8 schematically illustrates processing apparatus suitable for use with the applicator embodiment of FIGS. 6 and 7. As above, the elongated matrix strip 41 is fed from a roll 52 into contact with a film strip 53 between the pressure roller members 54 and 55. Takeup of the matrix 41 and film strip 53 are provided, respectively, by the takeup reels 56 and 57. As the matrix strip 41 is unwound from the roll 52, the spacer sheet 46 is removed and accumulated on the takeup reel 58. During movement of the matrix strip 41 between the roller members 54 and 55, compression of the matrix strip 41 and application of fluid reagent 42 to the film strip 53 occurs as described above.

FIG. 9 schematically illustrates another processing method wherein the matrix strip shown in FIGS. 1 and 2 is used to simultaneously process two separate film strips. As shown, the matrix strip 15 is fed from a roll 61 between the pressure roller members 62 and 63 and onto the takeup reel 64. Simultaneously, separate film strips 65 and 66 are fed between the roller members 62 and 63 on opposite sides of the matrix strip 15 before takeup by the takeup reels 67 and 68. Compression of the matrix strip 15 occurs as described above in connection with FIG. 3. However, in this case, fluid processing reagent 18 impregnated within the matrix strip 15 is forced out of the matrix strip 15 through both front and rear surfaces 16 and 17 and into contact with both film strips 65 and 66. Thus, simultaneous processing of two separate film strips is obtained with a single processing reagent applicator strip 15.

Although the invention is particularly well suited for continuous processing of roll film, the described viscous reagent impregnated applicator matrices can be used also for batch processing of separate film frames. For that application, a separate sheet of impregnated applicator matrix and a film frame to be processed are brought into surface contact and passed between a pair of pressure rollers that produce the desirable reagent spreading described above. It should be appreciated, however, that spreading of the applied reagent over the surface of the film can be produced in other ways. For example only, an impregnated matrix strip and a film strip being processed can be fed at different linear speeds between a pair of stationary pressure applicators (not shown). The different linear speeds produce relative movement between the matrix strip and film strip in a direction parallel thereto so as to produce the desired spreading of reagent fluid.

Obviously, many modifications and variations of the present invention are possible in light of the above teachings. It is, therefore, to be understood that within the scope of the appended claims the invention can be practiced otherwise than as specifically described.

What is claimed is:

1. A photographic film processing material comprising a sorbent compressible matrix having a front applicator surface and a back surface, said applicator surface being adapted to contact the exposed surface of photographic film, and said applicator surface having open pores communicating with the interior portions of said matrix, and a viscous liquid photoprocessing reagent impregnated in the interior portions of said matrix and adapted for discharge through said open pores in response to compression of said matrix, said viscous liquid processing reagent having a viscosity of at least 1,000 centipoises, said matrix also having therein a boundary layer portion substantially free of said liquid photoprocessing reagent and being located between one of its surfaces and the interior portions of said matrix which contain the viscous liquid photoprocessing reagent.

2. Photographic film processing material according to claim 1 wherein said matrix is an elongated strip wound in a cylindrical roll.

3. Photographic film processing material according to claim 2 wherein said boundary layer portion comprises matrix layers coextensive with and directly adjacent to both the front and rear surfaces of said strip.

4. Photographic film processing material according to claim 2 wherein said boundary layer portion comprises a matrix layer coextensive with and directly adjacent said front surface of said matrix strip, and including spacer sheet means coextensive with and contacting said rear surface of said matrix strip.

5. Photographic film processing material according to claim 1 including non-compressible matrix support means including a bottom wall and side walls partially enclosing said matrix.

6. Photographic film processing material according to claim 5 wherein said matrix is an elongated strip including edge surfaces, said matrix support means comprises a flexible elongated band, said bottom wall supports said rear surface of said matrix strip, said side walls cover said edge surfaces of said matrix strip, and said matrix strip and said support band are wound into a cylindrical roll.
